HAIR CLIPPER

Leo J. Wahl, Sterling, Ill., assignor to Wahl Clipper Corporation, Sterling, Ill., a corporation of Illinois

Application January 7, 1933, Serial No. 650,669

8 Claims. (Cl. 30—1)

My invention relates to hair clippers and is an improvement on that type of clipper shown, for example, in my co-pending application Serial Number 545,964, filed June 22, 1931, for Clipper blade control, Patent No. 1,895,183, dated January 24, 1933.

In this type of clipper, the comb and the cutter blade are so mounted that by movement of the comb angularly about a pivotal mounting on the clipper frame, an endwise sliding movement is effected between the comb and cutter blade so as to vary the coarseness of the cut.

The present invention has for its principal purpose the provision of a combined cover member and comb supporting member which will serve not only as a means for supporting the comb but will also enclose and protect the working parts such as the driving arm for the cutter blade and its connections to the cutter blade.

My invention contemplates also the provision in conjunction with the cover member of a novel means for angularly adjusting the cover and comb.

My invention also contemplates in connection with the cover member mentioned, the arrangement of the cover in such fashion that although it does not disturb the cutter blade in operation, it may be made to fit very closely thereto and thus exclude hair and other matter from within the cover.

I will describe the preferred form of my invention by reference to the accompanying drawing wherein—

Fig. 1 is a side view of the front portion of a clipper embodying my invention;

Fig. 2 is a longitudinal section through the front portion of the clipper showing the clipper adjusted for a very fine cut;

Fig. 3 is a similar section showing the clipper adjusted for the coarser cut;

Fig. 4 is a section on the line 4—4 of Fig. 1; and

Fig. 5 is a fragmentary view similar to Fig. 1 showing the change in the position of the operating member in adjusting the cut of the clipper.

Referring now in detail to the drawing, numeral 5 indicates the clipper frame, 6 and 7 are the comb and cutter blade respectively, and 8 is the driving arm which is preferably driven by an electro-magnet in a well known fashion, this electro-magnet being housed in the frame 5 and not shown herein as it forms no part of the present invention.

The comb 6 is carried by a combined support ing and cover member or head 9 which is pivoted

at both sides of the frame, for example by means of the members 10, so that it can swing about these pivots to cause angular movement of the comb 6 with respect to the clipper frame. This head 9, it will be noted, has a front portion 11 extended up and overlapping with the clipper frame at 12 and the side portions 13 and 14 also overlap with the sides of the frame which are cut out as indicated at 15 so that the cover is never separated from the frame, even in the extreme forward adjustment thereof.

The front 11 and sides 13 and 14 of the movable head 9 are cut away as indicated at 16. This provides clearance for the cutter blade. The cutter blade is always pressed against the comb so that it is always in the same relative plane with respect to the comb. The driving arm 8 moves slightly up and down during adjustment of the movable head but, owing to the fact that the cutter blade remains in the same plane with respect to the comb, the clearance between the cutter blade and the movable housing remains the same.

The cover at the sides near the back has the extensions 17 and 18 which are turned inward as shown most clearly at Fig. 4 and serve as a means for securing the comb in position. The screws 19 and 20 screw into these extensions 17 and 18 to firmly attach the comb.

In order to adjust the comb plate angularly with respect to the frame, I provide the lever 21 which lever is pivoted by means of the screw 22 to the clipper frame and this lever has a short arm 23 provided with the inturned cam member 24 for operating the cover member. The cam member 24 fits in the opening 25 of the side wall of the cover member and it will be clear from an inspection of Figs. 1 and 5 that as the lever is moved down from the position shown in Fig. 5 to the position shown in Fig. 1, the cam member 24 engages with the wall 26 of opening 25 to push the cover member outwardly and thus swing the comb and cover about the pivots 10. A limiting position is reached, however, when the member 24 strikes the web 27 at the back of the opening 25 and thus the web 27 and the member 24 function to limit the outer angular adjustment of the comb plate. In turning in the opposite direction the edges of the sides 13 and 14 engage with the shoulders 15 to limit the adjustment of the comb and cover in this direction. The arm 23 of the lever 21 is very short, and a small amount of friction opposing rotation of the lever is sufficient to prevent rotation of this arm by the pressure of the comb 6 when the clipper is being used. There is a spring washer 22a shown in Fig. 55

4 as being placed directly beneath the head of the screw 22 and bearing against the lever 21 to provide the necessary friction opposing a change of position of the lever 21.

5 It will be noted that the connection of the lever with the cover member 9 is substantially at the rear end of the cover and removed from the pivots 10. This has an additional advantage in that it enables one to have a rather large movement of the lever 21 for a small angular adjustment of the comb, thus making the adjustments capable of fine division and preventing any difficulty due to inability to properly gauge the adjustment.

10 Having thus described my invention, what I claim as new and desire to secure by Letters Patent is:

15 1. In a clipper, a clipper frame, a comb, a cutter blade, a driving arm for said blade, and means pivotally mounting said comb on the frame comprising a cover member pivoted on the frame and carrying said comb, a lever pivoted on said frame at a point spaced from the pivot of the cover member and connected with said cover member for changing its angular position with respect to the frame, said lever and member having cooperating portions limiting the angular movement of the member in one direction.

20 2. In a clipper, a clipper frame, a comb, a cutter blade, a driving arm for said blade and means pivotally mounting said comb on the frame comprising a cover member pivoted on the frame and carrying said comb, and means for adjusting said member and comb angularly with respect to the frame, said last named means cooperating with said member to limit the movement of the member away from the frame.

25 3. In a clipper, a clipper frame, a comb, a cutter blade, a driving arm for said blade and means pivotally mounting said comb on the frame comprising a cover member pivoted on the frame and carrying said comb, an adjusting lever pivoted on the frame and cooperating cam portions on the lever and cover for angularly adjusting the comb.

30 4. In a clipper, a clipper frame, a movable head pivotally mounted adjacent the end of the frame and projecting outwardly therefrom, a drive member projecting from the frame into the movable head, a comb blade fixed on the outer extremity of said head, a cutter blade slidable on the comb blade, said driving member being connected with the cutter blade for operating said blade and providing a pivot about which said cutter blade is angularly movable in response to angular adjustments of said head about its pivot, and means for adjusting said head about its pivotal mounting on the frame.

35 5. In a clipper, a clipper frame, a movable

head pivotally mounted adjacent the end of the frame and projecting outwardly therefrom, a comb blade fixed on the outer extremity of said head, a cutter blade slidable on the comb blade, the front edge of the head being cut away to permit projection of the cutter blade between the head and the comb blade, means carried by the frame and cooperating with said cutter blade to cause said cutter blade to move forward and backward on the comb blade in response to angular movement of said head, said cutter blade being movable angularly with respect to the frame to follow the angular movements of said head and thereby maintain the same clearance between the cutter blade and said front edge of the head in all positions of said head.

40 6. In a clipper, a clipper frame, a movable head pivotally mounted adjacent the end of the frame and projecting outwardly therefrom, a comb blade fixed on the outer extremity of said head, a cutter blade slidable on the comb blade, the front edge of the head being cut away to permit projection of the cutter blade between the head and the comb blade, means carried by said frame providing a pivotal axis for said cutter blade between the pivotal axis of said head and the comb blade, whereby angular movement of said head causes angular movement of the cutter blade about said pivotal axis, and longitudinal movement of the cutter blade on the comb blade.

45 7. In a clipper, a clipper frame, a movable head pivotally mounted adjacent the end of the frame and projecting outwardly therefrom, a comb blade fixed on the outer extremity of said head, a cutter blade slidable on the comb blade, the front edge of the head being cut away to permit projection of the cutter blade between the head and the comb blade, means carried by said frame providing a pivotal axis for said cutter blade between the pivotal axis of said head and the comb blade, whereby angular movement of said head causes angular movement of the cutter blade about said pivotal axis, and longitudinal movement of the cutter blade on the comb blade, said means comprising a driving arm pressing said cutter blade against the comb blade.

50 8. In a clipper, a clipper frame, a movable head mounted on one end of said frame for angular movement with respect to said frame, and projecting outwardly from said frame, a comb blade fixed on said head and spaced from the frame by said head, a cutter blade resting on said comb blade, said head and said comb blade being spaced apart at the front edge of said head, and said cutter blade projecting through the space between the comb blade and head, means to cause the cutter blade to slide forward and back on the comb blade in response to angular movement of said head, and means for moving said head.
